UNITED STATES PATENT OFFICE.

ALFRED J. DRAPALIK, OF ROCKY MOUNT, NORTH CAROLINA, ASSIGNOR OF ONE-HALF
TO FREDERICK W. FRANK, OF ROCKY MOUNT, NORTH CAROLINA.

GARBAGE-RECEPTACLE.

1,164,583.

Specification of Letters Patent. Patented Dec. 14, 1915.

Application filed June 2, 1914. Serial No. 842,482.

To all whom it may concern:

Be it known that I, ALFRED J. DRAPALIK, a citizen of Austria, residing at Rocky Mount, in the county of Edgecombe and 5 State of North Carolina, have invented new and useful Improvements in Garbage-Receptacles, of which the following is a specification.

The invention relates to receptacles, and 10 more particularly to the class of garbage receptacles.

The primary object of the invention is the provision of a receptacle wherein the cover thereof has mounted thereon a novel form 15 of chute for receiving substance to be delivered to the receptacle, the chute being automatically opened at its upper end and closed at its lower end and vice versa on actuating the foot treadle so that in this 20 manner odors from the interior of the receptacle will be prevented from escaping to the air, and the filling of the said receptacle is accomplished in a convenient manner.

Another object of the invention is the 25 provision of a receptacle wherein the closure therefor is operated by the foot of the user of the receptacle so that the substance to be dumped into the receptacle can be delivered to a chute which subsequently discharges 30 the same into the said receptacle, the slides for controlling the chute for the admission of the substance and the discharge thereof to the receptacle are controlled through the medium of a foot treadle, thus rendering 35 the said receptacle thoroughly sanitary and convenient for use.

A further object of the invention is the provision of a receptacle of this character which is simple in construction, thoroughly 40 reliable and efficient in its purpose, strong, durable, and inexpensive in manufacture.

With these and other objects in view, the invention consists in the construction, combination and arrangement of parts as will 45 be hereinafter fully described, illustrated in the accompanying drawing, and pointed out in the claims hereunto appended.

In the drawing:—Figure 1 is a side elevation of a receptacle constructed in accordance with the invention. Fig. 2 is a 50 similar view, showing the receptacle partly in vertical section. Fig. 3 is a perspective view of the cover to the receptacle, showing the slides for controlling the opening 55 and closing of the chute in the cover. Fig.

4 is a sectional view on the line 4—4 of Fig. 2.

Similar reference characters indicate corresponding parts throughout the several views in the drawing.

Referring to the drawing in detail, A designates the body of a receptacle which is preferably constructed from metal, although it may be made from any other suitable material, and B the lid or cover 60 which is removably engaged thereon. Formed on the lid or cover B at opposite longer edges thereof are guide flanges 5 in which is slidably engaged a base plate 6, the same having integral therewith and rising therefrom a substantially hopper shaped chute 7, the lower end of which is adapted to communicate with an opening 8 in the lid or cover B so that substances introduced into the chute 7 can readily discharge into the body A of the receptacle. Fixed to the base plate 6 at intervals are vertical supports 9 to which is fixed a guide plate 10 superposed above the base plate 6 and has formed 70 therein an opening 11 for communication with the chute 7 so that substances can be admitted to the chute 7 for the subsequent delivery thereof into the body of the receptacle. Formed in the base plate and in the guide plate 10 at opposite sides of the chute 7 are alining guide slots 12 in which are slidably fitted the connecting members 13 of the cut-off slides 14 and 15 respectively, the same being arranged relative to 75 each other so as to alternately close opposite ends of the chute 7, that is to say, that when one slide closes one end of the chute 7 the other end of the latter is opened, and in this manner the delivery of the substances to the body A of the receptacle is regulated 80 or controlled. The slide 15 is engaged in the guide flanges 16 formed on the guide plate 10 at the longer edges thereof, and this slide 15 at one end is formed with an upwardly and downwardly curled extension 85 forming a hand grip 17 which permits the manual manipulation of the slide in contradistinction to the automatic movement thereof as will be hereinafter fully described.

Fixed to the rim of the lid or cover B 105 at opposite points thereof are depending hangers 18 to which are swingingly connected the limbs 19 of a foot treadle 20, the said limbs being pivoted at 21 to the hanger, while connected to the treadle 20 are op- 110

erating cords or cables 22 which are trained over guide pulleys 23 suitably journaled on the base plate 6 and engaged with the connecting members 13 so that on depressing 5 the treadle 20 the slides 14 and 15 will be shifted simultaneously with each other for the opening of the chute 7 at one end and the closing thereof at the opposite end, and in this manner the admission of the substances to the chute and the discharge thereof therefrom is controlled. Rising from the 10 guide flanges 5 on the base plate 6 are vertical ears 24 to which are connected coiled retractile springs 25, each being connected 15 to the respective connecting members 13 uniting the slides 14 and 15 so that after the depressing of the treadle 20 the springs 25 will become active to move the slides 14 and 15 automatically for the closing of the 20 chute at the upper end and the opening of the same at its lower end.

The lid or cover B has pivotally connected thereto catches 26 which are adapted for detachable engagement with keeper lugs 27 25 mounted on the body of the receptacle, the catches and lugs being disposed at diametrically opposite points and serve to retain the lid or cover on the receptacle. Also exteriorly mounted on the body A of the receptacle at opposite points are handles which 30 permit the carrying of the receptacle from one point to another.

From the foregoing it is thought that the construction and the manner of operation 35 of the device will be clearly understood, and therefore a more extended explanation has been omitted.

What is claimed is:—

1. The combination with a receptacle, of 40 a closure therefor having an opening, a filling chute supported by the closure in alinement with the opening, slides disposed in parallelism above and below said chute, and means for simultaneously moving said 45 slides in the same direction to alternately open and close the opposite ends of the chute.

2. The combination with a receptacle, of 50 a closure therefor having an opening, a filling chute supported by the closure in alinement with the opening, slides disposed in parallelism above and below said chute, means for simultaneously moving said slides in the same direction to alternately open

and close the opposite ends of the chute, and 55 means for automatically returning said slides to normal position upon release of the first mentioned means.

3. The combination with a receptacle, of 60 a closure therefor having an opening, a base plate fitted upon the closure and having a filling chute disposed in alinement with said opening, a slide arranged between said closure and base plate, a second slide arranged above said chute, a connection between said slides, and means for moving 65 said slides simultaneously in the same direction to alternately open and close the opposite ends of the chute.

4. The combination with a receptacle, of 70 a closure therefor having an opening, a base plate fitted upon the cover and having a filling chute rising therefrom and disposed in alinement with said opening, a slide 75 arranged between the closure and said plate, a second plate disposed above the chute and in parallelism with the first mentioned plate, a slide mounted on the said second plate, a connection between said slides, and means for simultaneously moving said slides in the 80 same direction for alternately closing the opposite ends of the chute.

5. The combination with a receptacle, of 85 a closure therefor having an opening, a base plate fitted upon the closure and having longitudinally disposed slots at the opposite sides thereof, a filling chute rising from said plate and disposed in alinement with said opening, a slide arranged between the closure and said plate, a second plate disposed above said chute and having longitudinally disposed slots adjacent the opposite sides thereof, a slide mounted upon said second plate, members connecting said slides and movable through said slots, means for 95 simultaneously moving said slides in the same direction for alternately closing the opposite ends of the chute, and means for automatically turning the slides to normal position upon release of the first mentioned 100 means.

In testimony whereof I affix my signature in presence of two witnesses.

ALFRED J. DRAPALIK.
